UNITED STATES PATENT OFFICE

WILLIAM J. DUVALL, OF ST. LOUIS, MISSOURI, ASSIGNOR TO SMITH & DAVIS MANUFACTURING COMPANY, OF ST. LOUIS, MISSOURI, A CORPORATION OF MISSOURI

FOLDING DAVENPORT OR BED

Application filed July 26, 1928. Serial No. 295,502.

This invention relates to devices of the character as may be extended to form a bed or collapsed to provide a davenport or couch. More particularly, the invention relates to 5 that type employing in addition to springs, also a mattress, although it will be understood that the invention, as to some of its features, is applicable to other types of structures of this nature.

10 One of the objects of this invention is to provide a structure of the character described, whereby the space between the sections is increased to a maximum without increasing unduly the height of the superposed sections while permitting substantial springs 15 and a mattress of substantial thickness to be interposed therebetween.

Another object is to provide a structure of the character described, in which there 20 will be sufficient clearance between the top and bottom sections while they are moving into superimposed relation, as to avoid interference with a mattress of substantial thickness.

25 Another object is to provide a structure of the character described, in which the sections, and more particularly the top section, will be firmly supported in collapsed, as well as extended positions.

30 A further object is to provide a device of the character described, which will be simple in construction, effective and reliable in its action, and durable and economical to manufacture.

35 Further objects will appear from the detail description, taken in connection with the accompanying drawings, in which—

Figure 1 is a perspective view of a davenport fixture embodying this invention and 40 showing the same in extended position, the spring and mattress being substantially omitted;

Figures 2, 3, 4 and 5 are end views, showing the fixture in various positions;

45 Figure 6 is an end view of a davenport frame, showing the method of attachment; and

50 Figures 7 and 8 are views similar to Figures 5 and 2, respectively, but showing another embodiment of this invention.

Referring to the accompanying drawings, and more particularly to Figure 1, the fixture, which is arranged to be placed in a suitable davenport frame, is generally of structural iron, in the form of L's. It comprises a pair of end supports 1, each having a flange 2 adapted for mounting on the brackets 3 and 4 on the end 5 of the davenport frame. The supports may be secured in any suitable manner, as by bolts taking through the perforations 6 and 7 in the flange 2 and bracket 3, and by a rivet 8 on the bracket 4 taking into a slot 9 on the flange. This is only one means of mounting, which may be varied to suit requirements.

A top section 10 and a bottom section 11 each consists of a suitable framework for supporting a spring frame 12, the individual coil springs of which are shown at 13. It is to be understood, however, that any other type of spring may be employed.

Each support 1 has a raised bracket 14 for a pair of levers 15 and 16 pivoted thereon at 17 and 18 and pivoted to the top section at 19 and 20. The lever 15 has a piece 21 connected by a brace 22 with the body of the lever so as to provide a rearwardly projecting arm, which has a pivot 23 connecting it with the bottom section at its front. Between the rear of the bottom section and each bracket 24 is a strut 25, whose upper pivot 26 moves in a slot 27 in the upper section, while its lower pivot 28 moves in a slot 29 in the support. The pivot 27 is connected by a link 30 with an arm 31 on the lever 16. A spring 32 connects the support 1, and more particularly the bracket 33 thereon, to an arm 34 on the link 29, while a spring 35 connects the bracket 32 to the front side rail 36 of the bottom section 11.

A foot 37 on the strut 24 is arranged to engage the frame of the top section to support the same in closed position. A leg 38, pivoted at 39 on a bracket 40 on the top section, is connected by a link 41 with the lever 15. A clip 42 on the lever 15 provides a bearing for the lever 16. It will be understood that the parts are duplicated at each end of the fixture, and in order to secure unison in 100

operation, a truss bar or shaft 41 connects the arms 15.

The operation of the structure will now be readily understood, especially by reference to Figures 2 to 5, inclusive, which show the successive positions from collapsed to extended positions. The arms 15 and 16 form means whereby the top section may be moved to positions beside and above the bottom sec-

tion. As this top section is swung on the levers, the arm 21, by its direct pivotal connection with the front of the bottom section, supplemented by the connection from the arm 30 through the link 29 to the strut 24, will cause corresponding movement of the bottom section from collapsed to extended position. It will, however, be noted that, on account of the particular construction employed and on account of the fact that the bracket 14 raises

the pivots 17 and 18, the pivots 23, and in fact the bottom section, are moved to positions above and below the pivots of the levers 15. This not only provides ample space for the mattress between the sections, but also

causes the rear edge of the top section to readily clear the mattress at the forward edge of the bottom section when the parts are first moved to extended or collapsed positions, as shown in Figures 3 and 4. It will be seen that the springs 31 and 34 operate to balance the device so as to secure ease in operation, the springs 31 tending to rotate the links 29 about their lower pivots in such a way as to lift the top section from its position of Fig.

2. When the fixture is collapsed, as shown in Figure 2, the spring 31 will be under tension, while the spring 34 will be substantially slack. Upon the movement of the top section from collapsed to extended position, the

spring 31 will assist in that operation. During the latter part of the operation, however, the spring 34 is tensioned so as to be under tension when the device is extended. The spring 34 now comes into play to assist the collapsing of the device.

The operation of the leg 36 will be clear from Figures 2 to 5. As the top section moves to collapsed position, the feet 35 will engage the frame to firmly support the top section. As the top section moves to extended

position, the levers 16 will move into engagement with the clips 40, which now operate as bearings to support the top section at its rear end, where it meets the forward edge of the bottom section. When the device is ex-

tended, as shown in Figure 5, the strut 24 and the arm 21 are practically straight so as to support the top section as legs. It will, therefore, be seen that the sections are firmly supported both in extended and contracted positions.

In the embodiment shown in Figures 7 and 8, the numbers 21 and 22 have been combined into a single plate 50, to which the lever 15 is attached. In this case there is pivoted to the

bracket 14 at 18, in addition to the lever 16, a short bent lever 51, the lower end of which has connected thereto a spring 52 whose other end is attached to a bracket 53 on the support 70

1. In the extended position of the bed shown in Figure 7, the spring 52 is completely contracted so that it exerts no tension upon the lever 51. During the movement of the bed to collapsed position, however, the lever 16

comes into engagement with the bent-over end 54 of the lever 51 and subsequent movement of the lever 16 will then swing the lever 51 on its pivot 18 so as to stretch the spring 52. As the movement progresses, the tension

of the spring increases and the lever 51 is turned to a position as indicated in Figure 8. In this position the spring 52 operates to tension the lever 16 in such a way as to counter-balance the weight of the top section.

This not only renders it easier to lift the top section when extending the bed, but also tends to avoid a jar when the bed is collapsed.

While the invention is particularly applicable to davenports, it will be understood that this invention is applicable in many cases to other forms and types of structures of this general nature. It will, furthermore, be understood that certain features and sub-

combinations are of utility and may be employed without reference to other features and sub-combinations; that is contemplated by and is within the scope of the appended

claims. It is, furthermore, obvious that various changes may be made in details, within the scope of the appended claims, without departing from the spirit of this invention;

it is, therefore, to be understood that this invention is not to be limited to the specific details shown and/or described.

Having thus described the invention, what is claimed is:

1. A folding davenport or bed comprising, end supports, a top section, a bottom section, forward and rear levers pivoted on each sup-

port and connected with said top section 110, adapted to move the latter to positions be-

side and above said bottom section, means for moving said bottom section vertically includ-

ing pivots connecting the front of said bot-

tom section with arms extending laterally 115, from the forward of said levers, movable struts connecting the rear of said bottom section with said supports, and link connec-

tions from said struts to the rear of said levers.

2. A folding davenport or bed comprising, end supports, a top section, a bottom section, levers pivoted on each support and connected with said top section adapted to move the lat-

ter to positions beside and above said bottom section, pivots connecting said bottom section, with a pair of said levers, movable struts be-

tween the rear of said bottom section and said support, and operating link connections from said struts to the other pair of said levers.

3. A folding davenport or bed comprising, end supports, a top section, a bottom section, levers pivoted on each support and connected with said top section adapted to move the latter to positions beside and above said bottom section, pivots connecting said bottom section with a pair of said levers, struts between the rear of said bottom section and said support, slideable connections between said struts and said supports, and operating connections from said struts to the other pair of said levers. 5
4. A folding davenport or bed comprising, end supports, a top section, a bottom section, levers pivoted on each support and connected with said top section adapted to move the latter to positions beside and above said bottom section, pivots connecting said bottom section with a pair of said levers, struts between said bottom section and said support, said struts having slideable connections to said supports and said bottom section, and operating connections from said struts to the other pair of said levers. 10
5. A folding davenport or bed comprising, end supports, a top section, a bottom section, levers pivoted on each support and connected with said top section adapted to move the latter to positions beside and above said bottom section, arms extending rearwardly from the forward of said levers, pivots connecting said bottom section at its front with said arms, movable struts connecting the rear of said bottom section with said supports, and links operatively connecting said struts with the rear of said levers. 15
6. A folding davenport or bed comprising, end supports, a top section, a bottom section, levers pivoted on each support and connected with said top section adapted to move the latter to positions beside and above said bottom section, arms extending rearwardly from the forward of said levers, pivots connecting said bottom section at its front with said arms, struts between said bottom section and said supports and operatively connected with the rear of said levers, and slideable connections between said struts and said supports. 20
7. A folding davenport or bed comprising, end supports, a top section, a bottom section, levers pivoted on each support and connected with said top section adapted to move the latter to positions beside and above said bottom section, and feet connected to and movable with said levers so as to engage and support said top section when said top section is above said bottom section. 25
8. A folding davenport or bed comprising, end supports, a top section, a bottom section, levers pivoted on each support and connected with said top section adapted to move the latter to positions beside and above said bottom section, feet connected to and movable with said levers so as to engage and support said top section when said top section is above 30
- said bottom section, and bearings on the forward of said levers adapted for engagement by the rearward of said levers when said top section is beside said bottom section. 35
9. A folding davenport bed, comprising, end supports, a top section, a bottom section, forward and rear levers pivoted on each support and connected with said top section adapted to move the latter to positions beside and above said bottom section, means for moving said bottom section vertically including pivots connecting the front of said bottom section with arms extending laterally from the forward of said levers, a strut having means by which it is pivotally connected to the rear of said bottom section and to said support, one of said connecting means being also slideable, and means operatively connecting said strut with the rear one of said levers. 40
